R. STICKDORN.
FLUSHING APPARATUS.
APPLICATION FILED APR. 23, 1917.

Patented Jan. 29, 1918.

UNITED STATES PATENT OFFICE.

ROBERT STICKDORN, OF ZURICH, SWITZERLAND, ASSIGNOR TO ALBERT ECKSTEIN, OF NEW YORK, N. Y.

FLUSHING APPARATUS.

1,254,739.

Specification of Letters Patent. Patented Jan. 29, 1918.

Application filed April 23, 1917. Serial No. 163,882.

To all whom it may concern:

Be it known that I, ROBERT STICKDORN, a subject of the Emperor of Germany, residing at Zurich, Switzerland, have invented certain new and useful Improvements in Flushing Apparatus; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

This invention relates to a flushing apparatus for water-closets and other purposes of the type, in which upon an actuation of a distributing stepped piston at first a communication between a water supply pipe and the interior of an air-chamber is brought about, this communication being then interrupted, owing to a differential action upon the stepped piston, as soon as a certain pressure is reached in the air-chamber, whereupon the air-chamber is then put into communication with a flush-pipe.

In the hitherto known flushing apparatus of the kind referred to, the provision of a special inlet valve for the rinsing water is quite unavoidable and a certain space between air-chamber and a casing provided with connecting branches and adapted to take up the stepped piston and said inlet valve has also to be provided. In these known flushing apparatus the stepped piston is moreover actuated by the overpressure of the water produced in the air-chamber. Such a working has, however, the disadvantage that the pressure in the air-chamber is in consequence of unfavorable pressure-conditions no longer great enough to open this piston to a sufficiently great extent as soon as the air-chamber is put into communication with the flush-pipe through the agency of the stepped piston, so that the water current flowing into the flush-pipe is not strong enough to effect a perfect rinsing.

The flushing apparatus according to this invention is now characterized in that the distributing stepped piston is guided in a casing arranged inside an air-chamber consisting of two halves, the meeting ends of which inclose an obtuse angle, and that said piston finds also a guide in the flush-pipe when it is moved into the latter and after

that the coöperation between this piston and guiding means provided in said casing is interrupted. The differential piston is thereby adapted to effect directly a communication between the water supply pipe and the air-chamber. As a consequence of this, the construction of said casing may be considerably simplified and a special inlet valve for the water may be dispensed with.

A further advantage of this new apparatus consists in that the differential piston is acted upon from that moment in which its movement effecting a communication between the air-chamber and the flush-pipe is started during the whole duration of this movement by the pressure of the water prevailing in the supply-pipe, so that it is always moved in a sufficient manner for securing the proper communication between air-chamber and flush-pipe.

My invention comprises also novel details of improvement and combinations of parts that will be hereinafter more fully set forth and then pointed out in the claims.

The invention will now be more particularly described with reference to the accompanying drawing, which illustrates a constructional example of the invention.

In this drawing:

Figure 1 is a front view partly in section of this embodiment, and

Fig. 2 and Fig. 3 are sections on the line II—II of Fig. 1, showing the parts in different positions.

1 denotes a branch communicating with the water supply pipe not shown on the drawing and extending partly into the air-chamber 2. The latter consists of two halves joining at an obtuse angle. The joining inner ends of these halves are situated lower down than their outer ends.

3, 4 denote an axially movable stepped piston, the diameter of the piston part 4 exceeding that of the piston part 3, so as to constitute a differential piston. The piston 3, 4 is hollow and open at both ends. The parts 3, 4 are connected by a recessed portion 6.

5 denotes a handle for moving the differential piston 3, 4. The latter is guided in a stepped casing 7 having a round cross-section and welded to the air-chamber 2.

Branch 1 communicates with the interior of this casing 7. An adapting ring 8 is arranged in the lower part of the casing 7 where it acts as a support for ring 9 of 110

jointing material. 10 denotes a second adapting ring also arranged in the casing 7 and acting as a support for a ring 11 of jointing material. The two rings 9, 11 are kept in the proper position by means of a distance piece 12 provided with longitudinal slots. The latter acts also as a sieve preventing any solid substances in the water supply pipe from entering into the interior 10 of the casing 7 and it constitutes at the same time a pressure reducing member for the purpose of obtaining a noiseless working of the apparatus. A ring 13 provided with an internal thread is rigidly connected to the casing 7. A tightening nut 14 coöperates with ring 13. 15 denotes a cover limiting the upward movement of the piston 3, 4 and closing the casing 7. The described arrangement is such, that the piston 3, 4 may be taken out of the casing 7 upon a removal of cover 15. Upon unscrewing of ring 14, the parts 8, 9, 10, 11 and 12 may be easily and quickly taken out and inserted into the cylindrical casing 7. 16 denotes the flush-pipe with which is rigidly connected an adapting ring 17 coöperating with a ring 18 of jointing material. This pipe 16 is directly connected to the air-chamber 2.

The cycle of operation of the described 30 flushing apparatus is as follows:

When the parts are in their normal position, as shown in Fig. 2, the communication between the water inlet branch 1 and the interior of the air-chamber 2 is shut up and 35 the distributing piston 3, 4 is held in the lifted position by the pressure of the water. On the other hand the flush-pipe 16 communicates with the interior of the air-chamber 2.

40 If now the differential piston 3, 4 is pressed down by means of a pressure on the handle 5 of the same, in order to bring about a rinsing of the closet, first the communication between flush-pipe 16 and the interior of the air-chamber 2 is interrupted. Thereupon the recessed portion 6 of the distributing piston 3, 4 connects immediately 45 the branch 1 to the interior of the air-chamber, the piston being thereby also guided in the flush-pipe 16. Owing to this, the distributing piston 3, 4 is guided in all 50 its positions in a proper manner, this being even then the case when the recessed portion 6 prevents the guiding members 8, 9 from coöperating with said piston. As soon 55 as the communication between branch 1 and the interior of the air-chamber 2 is effected, the latter is filled with water until the pressure produced in this chamber is able to lift 60 the piston 3, 4 owing to differential action, in which case the prevailing water-pressure exerts in the well known manner on the piston part 4, having the larger diameter, a greater force than on the piston part 3. As 65 a consequence of this upward movement, the

communication between branch 1 and the interior of air-chamber 2 is shut up and hereupon the discharge from the air-chamber 2 toward the flush-pipe is then set free. As soon as this is the case, the water-pressure 70 acting upon the lower surface of piston part 3 assists the piston 3, 4 in its upward movement. As the water-pressure prevailing in the branch 1 acts during the whole upward movement of the piston 3, 4 upon the larger 75 piston part 4, the piston 3, 4 is moved under all conditions, and entirely independent of the pressure-variations occurring in the air-chamber 2 during the rinsing, to the desired degree in an upward direction, so that the 80 piston part 3 is always lifted sufficiently, the result of this being that a water current strong enough to effect a perfect rinsing of the closet is free to flow into flush-pipe 16. In the lifted position the distributing piston 85 3, 4 is nearly moved wholly out of the flush-pipe, so that in comparison with other known devices it reduces only by a very small degree the water-passage in the flush-pipe, and therefore an increased rinsing 90 action is obtained.

Owing to the fact that no special valve has to be provided for controlling the inlet of the water into the air-chamber, the construction of the apparatus may be considerably simplified, while at the same time a very reliable working is obtained. A further considerable advantage of the described flushing apparatus consists in that the flush-pipe acts at the same time as a guide for 100 the differential or distributing piston when the latter comes out of coöperation with certain guiding members provided in the casing 7, owing to the recess 6.

What I claim is:

1. In a flushing apparatus, an air chamber, a casing therein, a water supply conduit communicating with the casing, a flush-pipe arranged to communicate with the air chamber, a differential piston movably mounted in the casing and adapted to directly control communication between the air chamber and casing and between the air chamber and the flush pipe.

2. In a flushing apparatus, an air chamber, a casing therein, a water supply conduit communicating with the casing, a flush-pipe arranged to communicate with the air chamber, a differential piston movably mounted in the casing and adapted to alternately close communication between the air chamber and casing and between the air chamber and the flush pipe.

3. In a flushing apparatus, an air chamber, a casing therein, a water supply conduit communicating with the casing, a flush-pipe arranged to communicate with the air chamber, a differential piston movably mounted in the casing and adapted to successively close communication between the casing and

flush pipe and establish communication between the casing and chamber.

4. In a flushing apparatus, a receiving chamber, a casing therein, a water supply conduit in communication with the casing, a flush pipe normally communicating with the chamber, and a differential piston comprising means whereby communication between the chamber and flush pipe is normally established and communication between the casing and chamber is normally closed.

5. In a flushing apparatus, a receiving chamber, a casing therein, a water supply conduit in communication with the casing, a flush pipe normally communicating with the chamber, and a differential piston projecting through the casing into the chamber, said piston comprising means whereby communication between the chamber and flush pipe is closed and communication between the casing and chamber is established.

6. In a flushing apparatus, a receiving chamber, a casing therein, a water supply conduit in communication with the casing, a flush pipe normally communicating with the chamber, and a differential piston comprising an end portion adapted to close the flush pipe and a recessed portion through which communication is established between the casing and chamber.

7. In a flushing apparatus of the character described, an air-chamber, a casing mounted therein, a water supply branch directly connected to said casing, a flush pipe directly connected to said air chamber, and a differential piston guided in said casing and having a recessed portion, the latter being adapted to effect communication between said water supply branch and the interior of the air chamber while one end of the piston controls communication between the interior of the air-chamber and the flush-pipe, said piston being so arranged relatively to the water supply branch that in its normal position it is kept in the uppermost position by the pressure of the water and is moved during the whole duration of the movement effecting communication between the interior of the air-chamber and the flush pipe by the pressure prevailing in said supply branch.

8. In a flushing apparatus of the character described, an air-chamber, a stepped casing having a round cross-section and mounted in said chamber and rigidly connected thereto, a water supply branch connected to said casing, adapting rings ar-

ranged in the latter, packing members co-operating with said rings, a slotted distance piece between the rings and acting as a sieve and as a pressure reducing member, a tightening member for compressing the packing members, a differential piston guided in said casing and co-operating with the packing members, a cover for closing the casing, a handle on the differential piston and a flush-pipe directly connected to the air-chamber, said differential piston provided with a recessed portion adapted to effect direct communication between the water supply branch and the interior of the air-chamber while one of its ends controls communication between the interior of the air-chamber and the flush-pipe, the water supply branch being so arranged that it communicates with said casing laterally of the recessed portion of the differential piston when the latter takes up its normal position, so that the piston is kept in its lifted position by the water-pressure and is moved during the whole duration of the movement effecting a communication between the interior of the air-chamber and the flush-pipe through the agency of the pressure prevailing in said supply branch.

9. In a flushing apparatus of the character described, an air-chamber consisting of two halves, the meeting ends of which inclose an angle and are situated below their outer ends, a casing mounted in the meeting part of the two halves of the air-chamber, a water supply member communicating with the casing, a flush-pipe communicating with the chamber, and a differential piston guided in said casing and adapted to effect a direct communication between said water supply member and the interior of the air-chamber and to control the communication between said chamber and the flush-pipe.

10. In a flushing apparatus of the character described, an air-chamber, a casing therein, a water supply member communicating with the casing, a differential piston having a recessed portion, means in said casing for guiding the piston, a flush-pipe connected with the chamber, means in the flush-pipe for guiding the differential piston, said piston adapted to effect a direct communication between the casing and the air-chamber and to control communication between said chamber and the flush-pipe.

In testimony that I claim the foregoing as my invention, I have signed my name.

ROBERT STICKDORN.
